United States Patent Office

Des. 211,926
Patented Aug. 13, 1968

211,926

BOTTLE OR THE LIKE

John M. Kelly, Toledo, Ohio, assignor to The Sinclair
Manufacturing Company, Toledo, Ohio, a corporation of Ohio

Filed Jan. 16, 1967, Ser. No. 5,432

Term of patent 14 years

(Cl. D9—32)

Fig. 1.

Fig. 2.

Fig. 3.

FIG. 4.

FIG. 5.

FIG. 6.

FIG. 1 is a perspective view of a bottle or the like showing my new design;

FIG. 2 is a front elevational view thereof;

FIG. 3 is a rear elevational view thereof;

FIG. 4 is a top plan view thereof;

FIG. 5 is a side elevational view thereof; and

FIG. 6 is a view of a section thereof taken along line 6-6 of FIG. 4.

I claim:

The ornamental design for a bottle or the like, as shown.
